UNITED STATES PATENT OFFICE.

GEORGE A. PAFF, OF PORTSMOUTH, OHIO, ASSIGNOR TO WHEELING STEEL CORPORATION, OF WHEELING, WEST VIRGINIA, A CORPORATION OF DELAWARE.

WIRE REEL.

Application filed September 15, 1926. Serial No. 135,553.

This invention relates broadly to reels, and more specifically to reels or spools of the type employed as carriers for fence wire and the like.

5 The primary object of the invention is to provide a reel for wire which has formed therein central eyes of permanently circular and not readily distortable form for the reception of a supporting spindle or arbor 10 upon which the reel may be rotated in unwinding the wire therefrom.

A further object is to provide a structure of the character mentioned in which the eye-forming portions are made integral 15 with the end members of the reel.

In describing the invention in detail, reference is herein had to the accompanying drawings, in which—

Figure 1 is a perspective view of the invention; and—

Figure 2 is an end elevation of the same.

Referring to said drawings, 1 designates the parallel reaches of each of two similarly shaped members which are disposed in relatively fixed quadrangular body-forming relation. The said reaches 1 of each of said members are intermediate parallel portions of an elongated loop of approximately rectangular form made of a single length of 25 heavy wire, which loop has the opposite ends thereof bent outward at right angles to said reaches, forming parallel wings 2 of loop shape.

Associated with said body-forming members and complementing the wings 2 of the latter for forming cruciform reel ends or flanges are two cross members. Each of said cross members is formed of a single length of heavy wire bent to form opposite end 30 loops 3 and an intermediate eye 4, all disposed in the same plane. Moreover, each cross member comprises a connecting link between the two body forming members, the wings 2 of the latter being passed through 35 the body of said cross member prior to formation of the eye 4 of the latter and being jointed to the adjacent long side of said cross

member by means of embracing loops 5 formed at and exterior to the angles between said wings and the reaches 1, as shown in 50 Fig. 1.

The eye 4 of each cross member is formed by arcuately bending the midlength portions of the two long sides of the latter and disposing said arcuate bends 4^a in overlapping 55 complementary relation, and then rotating said bends one or more times to form the oppositely disposed twists 6 which serve to maintain said bends 4^a in fixed relation.

In prior structures of this type embodying 60 bearing eyes, the complementary eye-forming portions have been nonrigidly related and, therefore, the weight of the reel with its burden of wire coiled thereon, when mounted for rotation on a spindle, arbor, or other 65 support, has tended to distort the eye or to bend the same into an oblong form, thus rendering rotation of the reel objectionably irregular and difficult. This objection is overcome by the eye structure of the present 70 invention.

What is claimed is—

A reel for fence wire and the like, comprising two body forming members, each consisting of a substantially rectangular endless wire loop having its ends bent laterally to form parallel wings, and two cross members forming connecting links by which said body forming members are held in fixed relation, said cross members being associated 80 with said wings in the formation of reel ends of cruciform shape, each cross member consisting of an endless wire loop bent to form opposite end loops and a central eye, the latter being formed by overlapping arcuate bends provided in the opposite sides of 85 said cross members, which bends are rendered relatively fixed by the formation of twists at the points of their overlapping contact, and are disposed in the plane of 90 the longitudinal axis of said cross members and wings.

In testimony whereof, I affix my signature.

GEORGE A. PAFF.
